(57) **CLAIM**

The ornamental design for a motor cover, as shown and described.

DESCRIPTION

FIG. 1 is a top front perspective view of a motor cover showing our design;

FIG. 2 is a bottom rear perspective view of a motor cover showing our design;

FIG. 3 is a front elevation view of the motor cover of FIG. 1;

FIG. 4 is a rear elevation view of the motor cover of FIG. 1; FIG. 5 is a left side elevation view of the motor cover of FIG. 1;

FIG. 6 is a right side elevation view of the motor cover of FIG. 1;

FIG. 7 is a top plan view of the motor cover of FIG. 1;

FIG. 8 is a bottom plan view of the motor cover of FIG. 1; FIG. 9 is a reference view of the motor cover of FIG. 1; and, FIG. 10 is a cross section view along a view line 10-10 of the motor cover of FIG. 3.

The broken lines shown depict the portions of the motor cover that form no part of the claimed design.
